UNITED STATES PATENT OFFICE.

JOHN A. MANGOLD, OF MOUNDSVILLE, WEST VIRGINIA.

RULER.

SPECIFICATION forming part of Letters Patent No. 621,529, dated March 21, 1899.

Application filed January 22, 1898. Serial No. 667,587. (No model.)

To all whom it may concern:

Be it known that I, JOHN A. MANGOLD, a citizen of the United States, residing at Moundsville, in the county of Marshall and State of 5 West Virginia, have invented a new and useful Ruler, of which the following is a specification.

This invention relates to rulers, and has for its particular object to provide the ordinary ruler as now in common use with a simple and convenient calendar, which can be readily changed to suit each succeeding month, thereby providing in one article a combined ruler and perpetual calendar especially advantageous for use in school-rooms and for office work.

To this end the invention essentially consists in providing a ruler or similar article with an elongated groove and a column of 20 characters at one side of the groove in combination with a strip slidably fitted in the groove and having a column of characters co-operating with those at one side of the groove and improved means for retaining the strip 25 within the groove and preventing relative displacement thereof when adjusted to a fixed position.

In the drawings, Figure 1 is a perspective view of a ruler provided with my improvements. Fig. 2 is an enlarged detail transverse sectional view. Fig. 3 is an underneath perspective view of one of the spring cap-plates. Fig. 4 is a top plan view with the cap-plates removed.

Referring to the drawings, numeral 1 designates a ruler of any of the usual forms, in one face of which is provided a longitudinal slot 2, extending nearly the whole length of the ruler or to any suitable length, as desired. Mounted within the slot 2 I provide a slide or strip 3 somewhat shorter in length than the said slot in order to provide for the necessary adjustment of the slide within the same. This slide fits easily within the slot, 40 having its upper face preferably flush with the face of the ruler, and, as shown in Fig. 2, the lower edges are beveled or rounded, as at 4, thus permitting the slide to be easily and readily adjusted. The upper exposed face of 45 the slide is preferably divided into blocks or spaces 5 by means of transversed lines 6 pressed or sunk into the face of the slide.

Within these spaces are provided symbols designating the days of the week, arranged consecutively from one end of the slide to the other and comprising a period of five weeks and one or more days over. Similarly-formed spaces are provided upon the face of the ruler at one side and adjacent to the slide corresponding in number to the days of the month 55 and indicated by numerals arranged within said spaces consecutively from "1" to "31," inclusive. The spaces upon the slide and upon the face of the ruler are of the same length, and when any one of the spaces of the slide 60 is arranged to align with the first space upon the ruler the remaining spaces are accordingly aligned, and thus you have the days of the week arranged opposite the days of the month, consecutively from "1" to "31," in 65 their proper relation.

The column of spaces containing the numerals designating the days of the month should be arranged centrally between the ends of the slot, while the slide should be of 70 a length equal to at least six of these spaces, shorter than the slot, thus allowing the slide to be adjusted for a length equal to six spaces beyond either end of the month-column and limited in its movement in either direction 75 by the end walls 7 of the slot 2. By reason of the transverse lines 6 and the symbols designating the days of the week being pressed into the face of the slide a convenient roughened surface is provided, whereby the slide 80 may be effectively operated by placing the thumb or one of your fingers upon the face thereof and sliding the strip to its desired position.

To retain the sliding strip within the slot, 85 I provide metallic cap-plates 8, secured to the face of the ruler, at each end of the slot. These plates preferably extend the full width of the upper face of the ruler and are secured thereto at each side of the slot by suitable 90 tacks or rivets. As a means for locking the slide against accidental displacement after being adjusted to a desired position the inner extremities of the cap-plates are extended to 95 form spring-arms 9, of a width corresponding to that of the slide, and one of the arms is provided with a depending finger or lug 10, adapted to enter suitable notches 11, formed in the upper face of the slide. The finger or

lug 10 is preferably bent from the spring-arm 9 at its outer end and midway between the sides thereof, while the notches 11 are preferably arranged in the center of the width of the slide 5 and at the lines dividing the spaces. By this arrangement the slide is positively locked against accidental displacement and is always properly aligned with respect to the spaces of the month-column upon the face of the ruler.

10 The extremities of the spring-arms extend, respectively, to a point directly opposite the beginning of the month-column, so as not to cover up any of the symbols upon the slide. As will be readily understood, the spring-arms 15 bear upon the upper face of the slide to hold the same in position, and the arm having the locking finger or lug may be readily raised and disengaged from the notches in the slide by means of the finger-nail, knife, or any 20 other suitable means.

In Fig. 4 I have illustrated the calendar as set for the month of January, 1898, which began on Saturday. This view plainly shows the relative length of the slot and sliding strip 25 and also how the slide carrying the symbols for the days of the week may be adjusted to suit the several months of the year.

As my improvements may be applied to T-squares, triangles, or any of the other similar 30 or analogous articles, and also as various changes in the mounting and operation thereof may be made without departing from the spirit and scope or sacrificing any of the advantages of my invention, I do not wish to be 35 understood as limiting myself to the precise construction and arrangement of details as herein shown and described.

Having thus described the invention, what is claimed as new is—

40 1. A ruler or similar article provided with an elongated groove, and a column of characters at one side of the groove, a strip slidably fitted in the groove and of a shorter length than the same, said strip having a column of

characters coöperating with those at one side 45 of the groove, and retaining-plates closing in the ends of the groove, one of said retaining-plates having an interlocking-catch engagement with one end portion of the slide, substantially as set forth. 50

2. A ruler or the like, provided with a longitudinal slot in one face thereof, a slide adjustably mounted within and somewhat shorter in length than the slot, and cap-plates secured to the body of the ruler at each end 55 of the slot, said cap-plates being provided with spring-arms engaging with the top face of the slide, and one of said spring-arms having a lug or finger for engagement with notches in the upper face of the slide, substantially as and for the purpose set forth. 60

3. A ruler or the like, provided with a slot, a sliding strip adjustably mounted to move longitudinally within said slot, and carrying a column of grouped characters representing 65 the days of the week, a stationary column of characters representing the days of the month arranged adjacent to and parallel with the column of characters upon the sliding strip, and a cap-plate arranged at each extremity 70 of the slot, each cap-plate having a spring-arm resting upon the upper face of the sliding strip to retain the same within the slot, one of the spring-arms having a lug or finger for engagement with notches provided in the 75 upper face of the sliding strip, whereby the said strip may be locked against accidental displacement, after the sliding strip has been adjusted to any desired position, substantially as shown and described. 80

In testimony that I claim the foregoing as my own I have hereto affixed my signature in the presence of two witnesses.

JOHN A. MANGOLD.
